UNITED STATES PATENT OFFICE.

GEORGE T. JOHNSON, OF MELROSE, MASSACHUSETTS.

ROLL-PAPER.

1,093,334.

Specification of Letters Patent. Patented Apr. 14, 1914.

Application filed April 26, 1913. Serial No. 763,795.

To all whom it may concern:

Be it known that I, GEORGE T. JOHNSON, a citizen of the United States, residing at Melrose, in the county of Middlesex, State 5 of Massachusetts, have invented a certain new and useful Improvement in Roll-Paper, of which the following is a specification, reference being had therein to the accompanying drawings.

10 The invention consists in improvements in wound rolls of paper suitable for use in roll paper holders on the order of the holder shown, described and claimed in my divisional application filed October 25, 1913, 15 Serial No. 797,172. The said wound rolls comprise a wound continuous length of paper, usually having transverse lines of weakening at distances apart corresponding with the lengths of the successive portions 20 intended to be detached separately in the form of sections or sheets for use as paper towels, toilet paper, and the like.

The improvements comprise a wound roll of paper or the like having as a permanent 25 part thereof a central nut-element or its equivalent permanently in connection with the opening or passage of the roll and adapted for engagement with a quick-threaded portion of a supporting shaft occupying 30 said central opening or passage as in my division application aforesaid. Also the special construction of core formed or provided with the said nut-element.

An embodiment of the invention is illustrated in the drawings, in which latter,—

Figure 1 is a plan view of a fixture or serving apparatus like that of the said divisional application, showing in section a roll of paper and the core or carrier for said roll, in accordance with my present invention. Fig. 2 is an end view of the said fixture with the wound roll omitted. Fig. 3 is a front view of the base or back-plate. Fig. 4 is an end view of the core or carrier for 45 the roll of paper. Fig. 5 is an opposite end view thereof. Fig. 6 is a sectional detail illustrating the locking means. Fig. 7 shows a preferred locking arrangement.

Having reference to the drawings,—the 50 frame-ports of the fixture as shown herein comprise the base or back-plate 1 and the two side-arms 2, 2^a. For the pur-

pose of detachably connecting the said arms with the said plate without the use of screws, rivets, or other like fastenings, and providing a hinge connection which will enable the arms to be swung outward and backward to permit the application of a roll of paper, each of the arms is formed at its rear end with widely separated upper and lower ears 60 or lugs 3, 3, and also is provided at such end with a pintle 4 constituted by a wire secured in said ears or lugs and extending from one to the other thereof. In addition, the plate 1 is formed at each end thereof with a hook-shaped extension 5 proportioned and shaped to enter the space between the ears or lugs of the corresponding arm and between the wire pintle and the adjacent end of the body 65 of the arm. The vertical recess at the back 70 of the said extension receives the wire pintle and constitutes a bearing therefor. When the fixture is attached to a wall, the latter closes the said recess so that the wire pintle cannot leave its bearing. To limit the 75 inward swinging movement of the arm, so that in its working position the arm shall extend forward at right angles from the plate, the arm is furnished with a lateral shoulder 6 which makes contact with the 80 front face of the plate when the arm is swung inward into its working position. For the accommodation of the screws or bolts by which the fixture is attached to a wall or other support, the plate is formed 85 with transverse elongated slots 7, 7, through which the stems of the said screws or bolts may be passed. The slots are of fairly considerable length so as to enable the fixture to be fastened in place by screws or bolts 90 occupying holes already in the wall, for instance holes which have been made for use in attaching another fixture.

One of the side-arms, namely that marked 2, has attached thereto fixedly one end of 95 a shaft extending across to the other side-arm, 2^a. The said shaft is spirally threaded as at 8, Fig. 1, for a portion of its length next adjacent the side-arm 2 to which the shaft is attached. The thread is a quick 100 thread. The threading may be effected by grooving or milling the said portion of the shaft, or by forming the said portion polygonal in cross-section primarily and twisting

it, so that the angles shall form a multiple thread, or by applying a similarly twisted polygonal tube. The remainder of the length of the shaft is of smaller diameter and is smooth and unthreaded. Upon the smaller portion 9 of the shaft are sleeved a longitudinally expanding spiral spring 10, a collar 11, adapted to slide upon the shaft lengthwise thereof, a smaller longitudinally expanding spiral spring 12, and a tube 13, the end of the latter extending to the end of the small portion of the shaft. A socket to receive the said tube is provided in a boss 14 projecting transversely inward from the side-arm 2^a. The internal diameter of the socket is such as to provide a close but easy sliding fit for the tube 13.

The roll 15 of paper surrounds a cylindrical core or carrier 16 having two dia-
phragms or disks, each formed with a central hole for the passage therethrough of the supporting shaft. The disk 17 is pro-
vided with means to engage with the threaded portion 8 of the shaft. In Fig. 4, the
hole 17^a, through the said disk is quadran-
gular and the convex intermediate portions
of the edge of the hole enter the depressions
between the raised portions of the thread
of the shaft. Consequently, the disk 17 is a
nut-element. It engages with the threaded
portion of the shaft like an equivalent of a
nut. It centers the corresponding portion
of the core or carrier and roll with relation
to the shaft. The sliding collar 11 is shaped
and proportioned so as to enable it to pass
entirely through the hole 17^a, in the disk 17.
In this instance it is square in cross-section
and in such respect corresponds with the
hole 17^a. It also is tapering to enable
it to enter partway into the central hole
18^a of the disk 18 of the core or carrier,
so as to fit tightly within said hole and serve
to support and center the corresponding
portion of the core or carrier and roll.

As thus far described, the construction
and arrangement are such that when the
core or carrier, with a roll of paper thereon,
is mounted upon the shaft with the disk 17
engaged with the threaded part 8 of said
shaft and with the disk 18 engaged with the
exterior of the tapering collar 11, the core or
carrier and roll will be supported concentri-
cally with the shaft, and through the power
of the longitudinally expanding spring 9
will be caused to occupy a position nearer
the side-arm 2^a and with a clear space be-
tween the side-arm 2 and the next adjacent
end of the core or carrier. When now the
leading end of the strip of paper is pulled
upon so as to draw the paper from the roll
and cause the latter to turn, the turning
movement and the engagement of the disk
17 with the threaded portion of the non-
rotating shaft, will cause the core or carrier
and roll to travel endwise toward the side-

arm 2, thereby causing collar 11 to compress
the spring 10, until the increasing tension of
said spring causes the strip to tear across at
a line of weakening, or until the coils of said
spring close up together, or it might be until
either the core or carrier or the roll brings
up against a suitable stop, in this case the
said side-arm, whereby the endwise move-
ment of the core or carrier and roll, and
consequently the turning movement there-
of, will be arrested and the continued pull
upon the paper will cause the paper to part
at the line of weakening between the per-
iphery of the roll and the hand that is
pulling upon the paper. The thread of the
shaft being a quick thread, a small extent
of turning movement of the roll, i. e. one
or more turns thereof, will operate to carry
the roll endwise to the predetermined limit.
The endwise movement of the roll and core
or carrier compresses the spring 10 length-
wise between the collar 11 and the shoulder
at the end of the threaded portion of the
shaft. The parting of the paper releases
the roll so that the spring 10 is permitted
to act against collar 11 to press the core or
carrier and roll endwise toward the side-
arm 2^a, the engagement of the disk 17 with
the threaded portion of the shaft producing
a reverse rotary movement of the core or
carrier and roll. The roll comes to rest in
its primary position with the free end of
the strip of paper exposed in readiness to
be grasped.

The core or carrier usually in practice is
cylindrical. The holes in the disks 17 and
18 are formed centrally in the said disks, so
that the core or carrier and the roll thereon
naturally occupy a position concentric with
the shaft. The spring 12 between the sleeve
11 and the tube 13 serves as a yielding
cushion by which the return movement of
the core or carrier and roll thereon is
checked.

Having reference to the locking arrange-
ments, the close fit between the tube 13 and
the inner wall of the socket in connection
with side-arm 2^a into which it enters is such
that the tube can enter the socket only when
the tube and socket are presented in a
straight line with respect to each other. As
shown in Fig. 1, when side arm 2^a stands at
right angles to the plate, the inner end of the
socket is located at the inner side of a plane
at right angles to the plane of the plate and
passing through the pivotal axis of the said
side-arm. Assuming the parts to be related
as in Fig. 1, it will be apparent that force act-
ing with a tendency to swing the side-arm
2^a outward about the pivotal axis on which
the said side-arm swings will tend to cause
the socket occupied by the tube to become in-
clined in the direction of its length with re-
spect to the tube, so that one point of the
inner surface of the socket will cramp against
125

the extreme end of the tube at the point x at one side of the axis of the latter, and another point of such surface will cramp against the exterior of the tube at a point y 5 at the diametrically opposite side of the said axis. The cramping or binding will prevent relative endwise movement of the socket with respect to the tube. As the tube is held from passing off the end of the shaft 10 by the head that is formed in such end as in Fig. 6, the side-arm will thereby be locked in its inwardly closed position. The unlocking of the side-arm 2^a is effected by moving the said side-arm into such position that the 15 socket thereof is parallel with the exterior of the tube, thus rendering the tube free to have lengthwise movement within the socket, and then taking hold of the knurled exposed inner portion of the tube and sliding the 20 tube inward along the shaft. This of course can be done only when the roll has been completely unwound and the core or carrier slitted or partly broken or cut away for as long as any of the roll remains the tube is 25 covered and inaccessible. Spring 12 yields to permit this hand-effected inward sliding movement of the tube. When the tube has been moved inward the short distance necessary to relieve the pressure of its extreme 30 end against the interior wall of the socket during the outward swinging movement of arm 2^a , the cramping action will no longer occur when the said swinging movement is caused to take place, and consequently a 35 complete outward swinging movement of the said side-arm is permitted. When this has happened, the core or carrier may be removed and a roll wound upon another similar core or carrier may be placed upon the 40 shaft. The hinge-connection of the arm 2^a with the plate facilitates the operation of removing the core and placing a fresh roll upon the shaft, by rendering it possible to swing the said arm 2^a outward so as to give 45 the shaft a forwardly inclined position, in which the roll may more readily be applied. If this outward swinging movement of the arm 2^a and forward shift of the shaft is not desired, and if a rigid connection of the arm 50 2^a and the plate is found acceptable, then the said arm and the plate may either be formed integral with each other or fixedly connected together in any suitable manner. In the operation of closing the side-arm 2^a inward, 55 the end of the boss around the socket therein first encounters the end of the tube and slides the tube inward along the shaft until the axes of the shaft and tube and the socket are all in a straight line or coincide, and the 60 end of the tube registers with the entrance to the socket, whereupon the spring 12 projects the tube outward within the socket and the arm is permitted to assume its complete inward or working position. 65

The spring 12 acts to cushion the collar

11 in the return movement produced by the action of the spring 10. In addition, a stop-pin 20 applied to the shaft prevents too great a movement of the collar outward toward the arm 2^a . The said stop-pin also 70 backs up the spring 12 so that the tension thereof shall oppose any undertaking to pick the lock by pushing back the tube by means of a blade or wire introduced into the central opening of the roll alongside the boss of 75 arm 2^a when the roll has been caused to move over against the side-arm 2.

The boss of arm 2^a constitutes an internal support and bearing for the end of the roll which surrounds the same. 80

In the preferred locking arrangement of Fig. 7, the shaft is shorter than in the construction which has been described, the tube 13 is omitted, and the end-portion of the shaft has an axial bore receiving a pin 21 85 and a longitudinally expanding spring 22. The outer end-portion of the said pin extends beyond the end of the shaft, and normally is kept projected by the action of the spring to the limit fixed by a stop-screw 23 90 projecting from the pin 21 through a slot 24 in the tubular portion of the shaft, and adapted to engage with an end-wall of the slot. The action in locking and unlocking is essentially the same as in the case of the 95 locking tube of the prior figures. The pin 21 is drawn lengthwise inward to effect the unlocking by taking hold of the exposed head of stop-screw 23. 100

I claim as my invention:—

1. The novel article of manufacture comprising a wound roll of paper or the like sheet-material in continuous web-form, said roll having a central opening or passage, and a nut-element permanently in connection 105 with the said opening or passage and adapted for engagement with a quick-threaded portion of a shaft occupying said central opening or passage.

2. The novel article of manufacture comprising a wound roll of paper or the like sheet-material in continuous web-form, said roll having as a permanent part thereof a central core with passage therethrough for a supporting shaft, said core having a nut- 115 element adapted for engagement with a quick-threaded portion of said shaft.

3. The novel article of manufacture comprising a wound roll of paper or the like sheet-material in continuous web-form, said roll having as a permanent part thereof a core with central shaft-fittings, one thereof constituting a nut-element adapted to engage and coöperate with a quick thread upon a supporting shaft upon which the roll is 120 mounted. 125

4. The novel article of manufacture comprising a wound roll of paper or the like sheet-material in continuous web-form, said roll having as a permanent part thereof a 130

core with disks having central shaft-openings, one of said disks constructed as a nut-element adapted to engage and coöperate with a quick thread upon a supporting shaft occupying said shaft-openings.

5. The improved roll-core provided with disks 17, 18, having central shaft-openings, one of said disks constructed as a nut-element adapted to engage and coöperate with

a quick thread upon a supporting shaft occupying said shaft-openings.

In testimony whereof I affix my signature in presence of two witnesses.

GEORGE T. JOHNSON.
